[57] CLAIM

The ornamental design for a chair, as shown and described.

DESCRIPTION

FIG. 1 is a perspective view of the chair showing my new design;

FIG. 2 is a top elevational view of the chair design of FIG. 1;

FIG. 3 is a bottom elevational view of the chair design of FIG. 1;

FIG. 4 is a front elevational view of the chair design of FIG. 1;

FIG. 5 is one side elevational view of the chair design of FIG. 1;

FIG. 6 is a back elevational view of the chair design of FIG. 1;

FIG. 7 is the other side elevational view of the chair design of FIG. 1; and,

FIG. 8 is a perspective view of four chairs of my design grouped together, the broken lines are for environmental purposes only and form no part of the claimed design.
